UNITED STATES PATENT OFFICE

ARTHUR J. THERRIEN, OF NORTHBROOK, ILLINOIS, ASSIGNOR TO NATIONAL BRICK COMPANY, OF CHICAGO, ILLINOIS, A CORPORATION OF ILLINOIS

PROCESS OF MAKING BRICKS

Application filed January 23, 1926. Serial No. 88,342.

My invention relates to a process of making bricks, and it has for its principal object to provide a new method by which the manual handling of the bricks may be reduced to a minimum. By a process now in use, the green bricks as they come from the forming machine are piled on cars into solid unit piles containing approximately one thousand bricks each, the bottom layer of the bricks being spaced in such manner that a mechanically operated power fork is able to lift the pile bodily and transfer it to its position in a kiln. Heretofore it has been the practice to place the bottom layer of unit piles in rows across a kiln, with the rows separated from each other by a space equal to approximately one-half the width of the unit piles, a usual arrangement being that in which the unit piles are four brick-lengths in width and in which the rows are separated by spaces two brick lengths in width. After the placing of the unit piles in this arrangement by a power fork, it is necessary for a gang of workmen, equipped with the necessary extra green bricks, to reposition by hand a comparatively large proportion of the bricks on opposite sides of the spaces between rows for arching over such spaces so that the next succeeding layer of unit piles may be supported by the spaced piles and the arches, the arched spaces or tunnels being utilized for applying the heat for burning the green bricks, all as is well understood in the art.

It is the principal object of my invention to provide a method of handling green bricks by reason of which the work of completing the arches transversely through the kiln may be very greatly reduced. To this end, it is one of the objects of my invention to provide for forming the arches or arched tunnels in the unit piles as such piles are originally built up on the cars, the bricks being so arranged in such unit piles that the usual power fork may handle the pile in precisely the same way as is now done.

It is another object of my invention to improve the arrangement of the green bricks in a kiln and the arrangement of the unit piles and arched tunnels so that the burning of the bricks may be effected to better advan-

tage,—particularly by reason of the fact that the distance between the successive nozzles by which the heat is applied to the tunnels is decreased so that it is not necessary for the heat to spread laterally so far from each nozzle.

It is another object of my invention to provide a new arrangement of parts by reason of which the turning of the arches manually to the slight extent still necessary in the practice of my improved invention may be effected much more easily and expeditiously than has heretofore been possible.

According to the preferred method of practicing my invention, the arches are formed in the hacks which are built directly upon the transfer cars. In this manner nearly all of the arches are formed with only one handling of the bricks, whereas, in the previous methods, the bricks were hacked in spaced piles, and then the piles were rebuilt and additional bricks supplied to form the arches over the tops of the tunnels. The construction of a kiln according to my invention with arches of only one brick length in width, is wholly new and has been found to have inherent advantages that mark my method of piling and burning as a striking advance in the brick making industry, inasmuch as the cost of making the brick is greatly reduced and the brick is more perfectly burned, especially at the sides of the fire tunnels.

It is another object of my invention to improve in sundry details the method of making bricks as will be appreciated by reference to the accompanying drawings and the description thereof as hereinafter set forth. That which I believe to be new and desire to cover by Letters Patent is set forth in the claims.

In the drawings—

Fig. 1 is a side view, more or less diagrammatic, showing the arrangement of a unit pile of green bricks upon a car;

Fig. 2 is a side view of a power fork adapted for handling a unit pile of green bricks such as that shown on the car in Fig. 1, the upper end of the fork mechanism being shown in vertical section at the middle of the fork for better illustrating the turn-table;

Fig. 3 is a fragmentary view, being a sectional view taken on line 3—3 of Fig. 2;

Fig. 4 is a top plan view of the bottom layer of unit piles of unburned bricks in position in a section of a kiln, with a partial showing of the second layer of unit piles, and a showing at one corner of a third layer of unit piles;

Fig. 5 is an enlarged detail view showing a solid unit pile of green bricks in place in the middle portion of the kiln, with parts of two other unit piles adjacent thereto, the partial closing of the tunnel between two of the piles having been completed preliminary to the placing of the succeeding layer of unit piles thereon, while only a portion of the bricks have been repositioned for partially closing the space between the central pile and the third pile;

Fig. 6 is an enlarged detail view for illustrating the arched tunnels at the middle portion of the kiln, being substantially a section taken at line 6—6 of Fig. 4; and

Fig. 7 is a top plan view of a fragmentary portion of the bottom layer of unit piles in a kiln illustrating diagrammatically an alternative method of placing such piles.

The preliminary step in the practice of my invention in its preferred form comprises hacking the green bricks as they come from the brick machine, or the forming machine, into unit piles upon cars such as the car 15 illustrated in Fig. 1 having supporting wheels 16 thereon and having standards 17 at its opposite ends. In the unit pile as illustrated in Fig. 1, all of the green bricks are placed on edge throughout the pile in slightly spaced relation so that the combustion gases can pass therebetween. The bottom two layers of bricks are arranged in spaced relation to provide openings for the entrance of the tines of a power fork, the unit pile illustrated in Fig. 1 being provided for a power fork having fourteen of such tines in equally spaced relation from one side of the fork to the other side. The bottom layer of bricks are arranged in pairs, with suitable spaces between adjacent pairs, the bricks of the second layer being arranged directly above corresponding bricks of the first layer. Upon the upper edges of the bricks of the second layer, the succeeding layers are piled solidly "three on three" throughout the unit, except for the spaces left for providing the desired arches which are designated by the numerals 18 and 19. The portion of the unit pile or the pier between the arches 18 and 19 is four brick-lengths long, and each of the end portions of the unit pile is two brick-lengths in extent longitudinally of the pile and thus constitutes a half of a pier. The unit pile of Fig. 1 is four brick-lengths in width, the several tiers of bricks being preferably arranged in the same manner as is indicated for the outside tier as shown in elevation in Fig. 1. The first

four layers of bricks on top of the bottom two spaced layers are arranged regularly three on three. The next higher layer, however, is varied by placing the bricks 20 in position to jut out over the tunnels or spaces 18 and 19, so that the bricks 21 of the next higher layer are capable of completely closing the tops of the tunnels 18 and 19. The top two layers of bricks are laid solidly three on three throughout the entire length of the unit pile. The loose bricks 22 are supplied at the sides of the tunnel to fill the grip between the tines of the fork so that the bricks 23 may be picked up, the bricks 22 being preferably removed by a workman when the unit pile has been placed in position on the floor of a kiln.

I have found in practice that with a unit pile of bricks arranged as shown in Fig. 1, a fork 24 of approved form as now in use is capable of lifting the unit pile bodily and placing it in position on the floor of a kiln without disturbing the arched tunnels 18 and 19 of the unit pile, the fact that there are only eleven of the spaced supporting portions at the bottom of the pile instead of thirteen having no effect upon the operation of the fork.

The fork 24, as shown in Figs. 2 and 3 is supported by links 25 from a turn-table 26 supported by anti-friction bearings from a circular plate 27 which is adapted to be connected by any suitable means with a crane by which the fork and its load can be lifted and carried to any part of the kiln in connection with which the fork is to be used. The fork comprises a plurality of tines or arms 28 projecting from a bottom cross bar 29, each of the tines 28 being provided with a plurality of adjustable gripping plates 30 which are adapted to be closed together firmly upon the outer faces of a pair of bricks 31, as is best shown in Fig. 3, the grip upon a series of spaced pairs of bricks such as are illustrated at the bottom of the unit pile in Fig. 1 being such as to support the remaining bricks of the pile therefrom. Means is provided for releasing the gripping plates 30 from the spaced pairs of bricks so as to permit the fork 24 to be slid out of contact with the unit pile when the pile has been placed in position as desired.

As is well understood in the art, when the green bricks from the brick machine have been placed in unit piles upon cars 15 such as that shown in Fig. 1, the cars with the unit piles thereon are pushed into one end of a drying shed where the bricks are given the desired drying treatment preparatory to their transfer to the kiln for burning. After a suitable drying has been effected, the cars are taken with their loads to a point adjacent to the kiln, and the unit piles are picked up by the setting fork 24 one at a time and placed in position in the kiln for burning.

In Fig. 4 I have indicated a plurality of

unit piles as placed in position at each side of the kiln, one section of which is shown in said figure. In Fig. 4 are shown a considerable number of unit piles containing tunnels such as the pile illustrated in Fig. 1. It will be understood that the tunneled unit piles 32 at the outside face of the kiln will be placed in position first, the fork 24 being preferably withdrawn from the unit piles by movement toward the center of the kiln. In the arrangement shown in Fig. 4, four unit piles are placed in position one after another, with the arched tunnels 33 of one pile in alignment with the arched tunnels 33 of the adjacent pile. After the piles are arranged along one side of the kiln four-deep as illustrated, a like arrangement of unit piles 34 is placed in position at the opposite side of the kiln, such unit piles being also arranged four-deep from the outer face of the kiln toward the center, with the arched tunnels 35 in alignment. Inasmuch as it would be impossible to slide the fork out of engagement with the unit piles if an attempt should be made to continue the placing of the piles in the manner just described, I employ a different expedient for providing the arched tunnels at the center of the kiln. When this stage is reached I back on the cars 15 solid unit piles 36 of the same width as the width of the unit piles first described,—namely, four brick lengths. The solid piles 36 are set by means of the same fork or setting device successively in position in alignment with the piers at either side, and with spaces therebetween corresponding to and registering with the tunnel spaces of substantially one brick length in span so that the completed tunnels extend continuously across the kiln. At the end of the kiln, I place a solid unit pile 37, having a width of two brick-lengths to correspond to the size of the end portions of the unit piles adjacent thereto.

In Fig. 5 I have illustrated a solid unit pile 38, a portion of a similar solid unit pile 39 arranged adjacent to the pile 38 but separated therefrom by a space one brick-length in width, and a third solid unit pile 40 arranged on the opposite side of the pile 38 and similarly spaced therefrom. The space between the piles 38 and 39 is indicated by the numeral 41 and the space between the piles 38 and 40 is indicated by the numeral 42. The piles 38, 39 and 40 are representative of any three of the piles 36 of the arrangement shown in Fig. 4.

The above method of piling, that is, from the sides inwardly, and then longitudinally down the center, is particularly suitable for use with an overhead crane travelling longitudinally of the kiln floor for setting the piles or fork-fulls of brick. Since the movement of the crane is confined to the space between the overhead rails, which are placed on the

posts of columns 50—51, which are positioned along either side of the floor, and it is desired to utilize the space to the fullest extent, space for withdrawing the forks from the piles at either side may be left at the center, which space is filled by piles deposited transversely and from which the fork is withdrawn longitudinally. Obviously, the transverse piles could be put in at one side instead of in the center, without departing from the spirit of the invention, or if the withdrawal space for the forks is provided for in another manner, or is not required to be filled, the entire bottom layer of the clamp of bricks in the kiln may be set like the piles 32 and 34.

After the unit piles 38, 39 and 40 have been arranged in spaced relation as described, the edge bricks of the top layer at each side of the space between the unit piles are rearranged so as to jut out beyond the faces of the piles over the space between the piles, such jutting-out bricks being indicated in Fig. 5 by the numeral 43, all of the bricks along the space 41 having been repositioned for partially closing the top of the space 41 in said Fig. 5 to support the bottom bricks of the next courses and to prevent the same from falling through into the tunnel. Only a portion of bricks 43 have been repositioned along the space 42, however, between the unit piles 38 and 40. In the preferred practice of my invention, when the bricks 43 are slid outwardly to jut over the spaces between the piles, additional bricks 44 are inserted in the spaces left vacant so as to keep the top faces of the unit piles substantially flat and even.

After the unit piles 32, 34, 36 and 37 have been placed in position as illustrated and as above described, with the arched tunnels 33 and 35 in alignment with each other and with the spaces between the unit piles 36 also in alignment with the tunnels 33 and 35, and with the bricks 43 repositioned manually for partially closing the upper ends of the spaces between the unit piles 36, a solid layer of solid or untunnelled unit piles 45 is then placed in position, such unit piles being arranged in any desired suitable manner, the only requirement being that the piles be so arranged that the bricks shall extend lengthwise across the partially closed spaces between the unit piles 36 and 37 for preventing the bricks from falling out of position into such spaces. After the layer of unit piles 45 is placed in position, a third layer and any desired number of additional layers are placed in position one upon another as is well understood in the art, such unit piles being indicated by the numeral 46 in Figs. 4 and 6.

While I have described each layer of unit piles as being completed in succession before the next higher layer is started, it will be understood that this has been merely for clearness of illustration. In practice the work on

the several layers of the pile would ordinarily be carried on at the same time in receding terraces to suit the convenience of the workmen.

In Fig. 7 I have shown an alternative method of placing the unit piles in position. In this arrangement, a continuous row of solid unit piles 47 are placed in position end to end transversely of the kiln. A similar row of solid unit piles 48 are then placed in position with a space 49 between the rows corresponding to the spaces 41 and 42 of Fig. 5. Succeeding rows of solid unit piles 50 are then placed in position with a space 51 between each two rows. The spaces 49 and 51 extend clear across the kiln, being employed in lieu of the arches before described comprising the arched tunnels 33 and 35 and the partially closed spaces 41 and 42. The bricks of the top layer at opposite sides of the spaces 49 and 51 are then to be slid outwardly so as to extend a short distance over the spaces in the manner described in connection with the bricks 43 of Fig. 5. The next higher layer of unit piles can then be placed in position in precisely the same manner as is described above in connection with the arrangement shown in Figs. 5 and 6. While I prefer to employ the method as outlined in connection with Fig. 4 employing the two expedients for forming the transversely extending arched tunnels, I do not wish to limit myself to the use of the two methods of forming such arches as distinguished from using either of the methods exclusively to the extent that either of such methods is available for effective use by itself for attaining the desired result.

Prior to my invention the practice has been to make the arches two brick lengths in width, which has necessitated starting the jetting of the bricks at the fifth course. By my invention the jetting is only at the seventh or last course, and requires less labor and fewer extra bricks. The setting and burning is also more uniform than with the old practice with the wider arches, where it is customary to provide twenty-five arches for each million of brick. Now I use about thirty arches for each million of brick and obtain greater economy in labor with much greater speed of construction, and obtain much better results in the finished product. For example, it was previously necessary in setting the arches for the workmen to handle about four thousand bricks to the arch, while by my invention it is only necessary to handle about one hundred bricks for each arch. The burning has been reduced from about 76 hours to about 48 hours because the heat penetrates through the kiln much faster.

The kiln of bricks produced by my method has arches extending therethrough from one side to the other. After the usual sheathing with burned brick and scoving, or smearing with clay or brick-dust mixed with water to

close the interstices between the brick at the surfaces to form substantially tight outer walls, as is well understood in the prior art, the kiln is burned by firing the arches from both ends. This may be accomplished with any suitable fuel, but I prefer to employ oil burners using steam or compressed air for the necessary atomization and to force the fire into the arches to the center of the kiln.

I have found, as stated above, that with the narrower arches I can burn the brick at the lowest portion of the kiln more rapidly and thoroughly with less fuel. This is mainly for two reasons; first, because my process of stacking provides tunnels or arches which are closer together and the penetrating distance through the walls of the arches is decreased, and, second, because by the use of narrower arches the ratio of surface to volume of the arches or tunnels is very greatly increased. This can be more appreciated when it is considered that there are many more outlets in the spaces between the bricks in proportion to the amount of flame in my narrower arches than in the wide arches of the prior art. Also, it is easier to fill the arches with fire than was previously possible, and this can be done with less overburning and slagging of the bricks in the arches than has heretofore been possible. Although my invention is more especially intended for use in the production of common bricks, it is also adaptable for making bricks of a higher grade.

While I prefer, in general, to employ the arrangements as above described, it will be understood that I do not desire to be limited to the details of the method as described except so far as I may be limited by the claims, inasmuch as it is evident that departures might well be made from the practice as above described without departing from the spirit of my invention.

I claim:

1. The process of setting bricks in a kiln which comprises forming a plurality of individual piles of unburned brick, each pile having a transverse arch therethrough, and assembling said piles with the arches in alignment.

2. The process of setting bricks into a kiln which comprises forming a first plurality of individual piles of unburned brick, each pile having a transverse arch therethrough, assembling said piles in two parallel rows with the arches in alignment, forming a plurality of solid piles of unburned bricks, setting said solid piles between said rows with their adjacent edges in alignment with the edges of the arches formed in said first piles, jetting said solid piles to close the arches between them and then setting further solid piles upon the arches so formed.

3. The process of setting bricks in a kiln which comprises forming a plurality of tun-

nelled piles, assembling said piles with the tunnels in alignment, forming a plurality of solid piles, assembling said solid piles with the tunnelled piles by setting said solid piles with parallel adjacent edges in alignment with the edges of the tunnels, and jetting said solid piles towards each other to form an arch.

4. The process of setting bricks in a kiln which comprises forming a plurality of individual piles of unburned bricks, each pile having a transverse arch therethrough of substantially one brick-length in width and assembling said piles with arches in alignment.

5. The process of setting bricks in a kiln which comprises forming a plurality of individual piles of unburned bricks, each pile having two transverse arches therethrough, each of substantially one brick-length in width and separated by a pier substantially four brick-lengths in width, and each pile being substantially ten brick-lengths long, and assembling said piles with arches in alignment.

6. The process of forming a kiln of bricks for burning which comprises piling unburned bricks on edge into rectangular piles, each being ten brick-lengths long, four brick-lengths deep and having two transverse arches or tunnels each a brick length in width, forming a plurality of piles of substantially the same dimensions and of the same height without arches therein, assembling the tunnelled piles in contact with the arches in alignment at one side of the kiln floor, assembling the tunnelled piles in contact with the arches in the same alignment at the other side of the floor, setting solid piles with their longer side in alignment with the opposite edges of the tunnels between the tunnelled piles, and jetting the top layers of the solid piles towards each other to arch the space between them.

45 7. The process of forming a kiln of bricks for burning which comprises piling unburned bricks on edge into rectangular piles, each being ten brick-lengths long, four brick-lengths deep and having two transverse arches or tunnels each a brick length in width, forming a plurality of piles of substantially the same dimensions and of the same height without arches therein, assembling the tunnelled piles in contact with the arches in alignment at one side of the kiln floor, assembling the tunnelled piles in contact with the arches in the same alignment at the other side of the floor, setting solid piles with their longer side in alignment with the opposite edges of the tunnels between the tunnelled piles and jetting the top layers of the solid piles towards each other to arch the space between them, and setting a layer of solid piles over the tunnel containing layer previously formed.

8. The method of piling bricks into a tunnelled stack for handling with a fork which comprises forming a bottom layer two brick-width deep consisting of ten supporting groups of brick piled edgewise two brick thicknesses in width, and the group being spaced to receive a fourteen-tined fork, said layer omitting groups of brick between the fourth and fifth tines of the fork and between the tenth and eleventh tines of the fork, and piling bricks edgewise three on three on said piers, leaving arches one brick-length in width above the omitted groups.

9. The process of making bricks which comprises stacking unburned bricks into individual piles, each pile having a transverse arch therethrough, assembling the piles in contact with each other in a kiln with arches in alignment, superposing solid piles of unburned bricks upon said first pile to form a kiln and firing said arches to burn the kiln.

10. The process of making bricks which comprises stacking unburned bricks into individual piles, each pile having a transverse arch therethrough of a width substantially equal to the length of one brick, assembling the piles in a horizontal layer in contact with each other and with said arches in register, superposing unburned bricks to form a kiln and firing the arches to burn the kiln.

11. The process of making common building bricks which comprises setting unburned bricks in an open clamp kiln with substantially parallel transverse arches substantially a single brick length wide and of substantially uniform height through the bottom of the kiln and firing fuel in said arches from each end to burn the kiln.

12. The process of making building bricks which comprises setting unburned bricks into piles ten brick lengths long, four brick lengths deep and of a height in excess of seven brick widths, assembling a first layer of piles in rows separated by substantially one brick length, extending the bricks towards each other at the upper facing edges of the rows of piles to define transverse firing arches, then setting a layer of piles in solid formation upon said rows over said firing arches, completing the kiln by further layers of bricks in solid formation, then firing fuel in said fire arches to burn the bricks in the kiln.

13. The process of making bricks which comprises setting unburned bricks into a series of rectangular piles of a width of the order of four brick lengths, said rectangular piles being separated by fire box spaces of approximately one brick length wide, projecting the bricks at the upper adjacent edges of said piles out over said spaces to partially bridge said spaces, setting brick in solid formation over said piles and spaces to complete a kiln, then firing fuel in said fire box spaces to burn the bricks in the kiln.

14. The process of making bricks which

comprises setting unburned bricks in the form of an open clamp kiln and leaving substantially parallel transverse openings of only one brick length in width and of approximately seven brick widths high throughout transversely through the kiln, then firing fuel into both ends of said transverse openings to burn the kiln.

15. The novel method of handling unburned bricks to form an open clamp kiln which comprises hacking the bricks directly upon transfer cars and simultaneously forming transverse arches through the hacks, then assembling the hacks with their arches in alignment in a kiln.

16. The novel method of handling unburned bricks to form an open clamp kiln which comprises hacking the bricks directly upon transfer cars and simultaneously forming transverse arches through the hacks, then assembling the hacks with their arches in alignment in a kiln, and firing fuel in said aligned arches from each end to burn the bricks in the kiln.

25. 17. The method of making bricks which comprises setting unburned bricks in the form of an open clamp kiln with narrow arches only through the bottom of the kiln, said arches being of a width of approximately one brick length and of substantially uniform height, then firing fuel in both ends of the arches to burn the bricks in the kiln.

18. The method of manufacturing bricks which comprises forming the green bricks, manually piling the green bricks onto cars in oblong piles, during said manual piling of each pile forming transverse pick-up openings through the base of the pile and forming a firing arch transversely through the pile, drying the piles of bricks, picking up the piles from the cars by a lifting fork, setting said piles of dried bricks with their transverse firing arches in alignment in a kiln and firing fuel in said arches to burn the kiln.

45. 19. The method of manufacturing bricks which comprises forming green bricks, piling the green bricks onto cars in oblong piles and at the same time forming transverse pick-up openings through the base of each pile and a transverse firing arch through the body of each pile, picking up the piles of bricks from the cars by a lifting fork inserted in said pick-up openings, setting the piles with their transverse firing arches in alignment in a kiln and firing fuel in said arches to burn the bricks in the kiln.

20. The method of manufacturing bricks which comprises forming green bricks, piling the green bricks into unit piles and at the same time forming transverse pick-up openings through the base of each pile for the insertion of a lifting fork and forming transverse firing openings through the piles, picking up the piles of bricks by a lifting fork inserted in said pick-up openings, setting the

piles with their transverse firing openings in alignment to form parallel firing arches in the base of a kiln, piling additional bricks upon the tops of the aforesaid piles to form a kiln, and firing fuel in said arches to burn the bricks in said kiln.

21. The method of making bricks which comprises forming the unburned bricks, piling the unburned bricks into a kiln having parallel firing arches in the base thereof, said arches being of substantially a single brick length in width and of substantially uniform height throughout and separated by piles approximately four brick lengths in width and firing fuel in said arches to burn the

22. The method of making bricks which comprises forming green bricks in a brick machine, piling the green bricks as they come from the forming machine into unit piles of oblong plan with transverse arches therethrough, drying the piles, assembling the piles of dried bricks with their arches in alignment to form the base of a kiln, piling additional solid piles of bricks upon the base to complete the kiln and firing fuel in said arches to burn the bricks in the kiln.

23. The method of making bricks which comprises forming green bricks and as fast as they are formed piling the green bricks into unit piles four brick lengths in horizontal thickness, ten brick lengths in horizontal thickness and approximately nine brick widths high, and at the same time forming two transverse arches each of a single brick length in width through each unit pile, drying the unit piles, assembling the unit piles of dried bricks with their arches in alignment to form the base of a kiln and firing fuel in said arches to burn the bricks in the kiln.

24. The method of making bricks which comprises forming green bricks, as fast as they are formed piling the green bricks into oblong unit piles with pick-up openings through the base of each pile and arched tunnels extending transversely through each pile, drying the piles, picking up the unit piles and setting them together in a kiln with the tunnels in alignment to form firing arches through the base of the kiln and firing fuel in said arches to burn the bricks in the kiln.

25. The method of making bricks which comprises forming unburned bricks, piling them into an open clamp kiln with parallel transverse firing arches therethrough of substantially one brick length in width and firing fuel in said arches to burn the bricks in the kiln.
